UNITED STATES PATENT OFFICE.

VICTOR SUSSIN, OF CHICAGO, ILLINOIS, ASSIGNOR TO STEWART-WARNER SPEEDOMETER CORPORATION, OF CHICAGO, ILLINOIS, A CORPORATION OF VIRGINIA.

CAR HEATER.

Application filed February 12, 1926. Serial No. 87,731.

The purpose of this invention is to provide an improved construction of heater adapted to utilize the gaseous products of combustion such as the exhaust from an 5 internal combustion engine, the specific purpose of the invention being to obtain the largest radiating surface possible within a given floor area occupied by the structure, and also to obtain a sufficiently prolonged 10 or extended path of circulation of the gases in contact with exteriorly exposed radiating surfaces to extract as large a proportion as possible of the heat units by radiation; and to accomplish this result by construction 15 which can be economically produced and require a minimum attention for keeping it in order and minimum cost for repairs. It consists in the elements and features of construction shown and described 20 as indicated in the claims.

In the drawings:—

Figure 1 is a plan view of a construction embodying this invention having the radiating element of the heater enclosed by a 25 perforated screen which is partly broken away to show the outlines of the radiating element.

Figure 2 is a perspective view of the 30 radiating element with the screen removed and showing the pipe connections thereto.

Figure 3 is a medial longitudinal vertical section of the radiator.

Figure 4 is a transverse vertical section of the radiator at the line 4—4 on Figure 3.

Figure 5 is a perspective view of the 35 radiator dissected, that is, having its three principal elements which in the construction are permanently united, shown separated from each other.

The screen, A, in which the radiator is 40 enclosed forms no part of this invention and may be in any form and need not be further described. The radiator indicated as to its totality by reference letter, B, comprises 45 two stamped sheet metal members, 10 and 20, each being stamped to produce a cavity open at one side of the stamping, the two members being formed in respect to these cavities so that when assembled with the cavities facing each other they constitute mutual 50 closers for each other's cavities (except as the pipe connections hereinafter mentioned). The stamped member, 10, however, has its cavity, 11, shorter than the cavity, 21, of the member, 20, that of the

latter being substantially the entire length of the member except as to the marginal flange, 22, which corresponds dimensionally to the marginal flange, 12, of the member, 10; so that upon the two members being 5 brought together with their flanges mated, each closes the other's cavity as stated. The two members are, however, separated by a third member, 30, constituting a partition plate which is peripherally dimensioned 60 correspondingly to the flanges, 12 and 22, of the stamped members, so that when interposed between the two members assembled with their cavities facing, the peripheral outlines of the three parts, coincide; and 65 upon said three parts being permanently secured together over the area of the flanges, 12 and 22,—such securement being preferably by electrically welding,—by reason of the cavity, 11, being shorter than the 70 cavity, 12, and stopping short therefore of the end of the stamping, 10, there remains 75 at 13 a portion of the web of the stamping, 10, beyond the end of the cavity, 11, over the whole extent of which the partition, 30, laps; and the securement of the partition to the member, 10, by electrically welding is 80 desirably extended over its entire area except as to an aperture therethrough for the pipe connection hereinafter mentioned. 85 The inlet and outlet pipe connections for the heating gases are provided for admitting the gases to the cavity of one of said members at one side of the partition and discharging the gases at the corresponding end 90 of the other cavity on the other side of the partition, the partition being apertured as seen at 31 at the end opposite that at which the pipe connections are made, so that the gases entering at one end of the cavity of 95 one stamping member,—as the member, 10,—are compelled to circulate through the entire length of that cavity to reach the apertures, 31, in the partition for passing 100 above the partition and returning through the whole length of the cavity in the member, 20, to reach the outlet pipe connection. The inlet pipe connection, 40, as it will be 105 understood from the foregoing, is attached at an aperture in the bottom of the stamping, 10. The outlet pipe connection, 50, is attached at the area, 13, of lap of the web of the member, 10, upon the partition, 30, registering apertures being made through 110 said web and partition for connecting said

outlet. Both the inlet and the outlet connections, 40 and 50, are secured at the apertures at which they are mounted by being originally diametered exteriorly for fitting accurately in said apertures, and then crimped to grip the margin of the apertures at both sides as may be clearly understood from the drawings. It is entirely feasible, as mechanics familiar with this art will 10 understand, to produce a perfectly fluid-tight junction by thus crimping the pipe nipple, consisting of drawn tubing, upon the margin of the aperture in which it is thus fitted.

15 Each of the stampings, 10 and 20 is formed with longitudinally extending corrugations, 15, 15, in the lower member, 10, and 25, 25, in the upper member, 20, said corrugations in each case stopping a little 20 short of the pipe connections leading into and out of the stamping cavities respectively, as seen at 15^a and 25^a. At the opposite end said corrugations similarly stop a little short of the location of the apertured 25 area, 31, of the partition, 30. These corrugations are desirably of such depth as to make the flow path of the gases considerably restricted in cross section as compared with the total cross sectional compass of the cavities of the said stampings beyond the length 30 of the corrugations. This, it will be understood, is for two purposes, first, to increase the radiating area of the fixture, and second, to retard the flow of the gases to an extent 35 which will afford opportunity for them to give up their heat. Preferably the aperturing in the partition, 30, through which the gases pass from one side to the other of that partition is in the form of a plurality of slots 31 as seen in Figure 5. This 40 is preferred for the purpose of breaking up the gases and somewhat restricting their flow.

45 The inlet and outlet pipes, 70 and 80, connected to the pipe connections, 40 and 50, respectively, it will be understood, lead from and back to the engine exhaust conduit, of whatever form, by which the exhaust gases are led to the muffler or for 50 final discharge. The present invention is not concerned with the means for determining the flow of the exhaust gases to the heater or the contrary; and any suitable

construction may be employed for this purpose.

55

I claim:—

1. A heater for utilizing gaseous products of combustion,—as the exhaust gases of an internal combustion engine,—consisting of a pair of stamped metal members each formed 60 with a longitudinally extending cavity, said members adapted to mutually close each other throughout their longitudinal extent in common when assembled with said cavities facing each other, and a partition plate 65 interposed between said members and united fluid-tight thereto at the margins of their cavities, said members having pipe connections leading into their respective cavities at opposite sides of said partition near the 70 same end of the assembled structure, the partition being apertured near its opposite end for discharge of gases from one side of the partition to the other.

2. In the construction defined in claim 1 75 the mated stampings having longitudinally extended instruck corrugations of depth causing them to approximate the partition, said corrugations in the two members as to their longitudinal extent stopping short of 80 the pipe connections respectively.

3. In the construction defined in claim 1 one of said stamping members having its cavity stopping short of the length of the cavity of the other member at one end, the 85 web of the first mentioned member being of the full length necessary for lapping the entire length of the cavity of said other member and having in its extent beyond said cavity the opening for pipe connection 90 to the longer cavity of said other member.

4. In the construction defined in claim 1, one of said stamping members having its cavity stopping short at one end of the length of the cavity at the other member, 95 the pipe connection to said other member being made for leading into its cavity at the part thereof which extends beyond the cavity of the first mentioned member; whereby the connections to the two members may be at the same side of the assembled structure.

In testimony whereof I have hereunto set my hand at Chicago, Illinois, this 5th day of February, 1926.

VICTOR SUSSIN.
